UNITED STATES PATENT OFFICE.

FRANK E. HOLMES, OF PASADENA, CALIFORNIA, ASSIGNOR TO BLOOMFIELD-HOLMES CORPORATION, OF PASADENA, CALIFORNIA, A CORPORATION OF CALIFORNIA.

COMPRESSOR.

Application filed September 17, 1925. Serial No. 56,861.

My invention relates to a novel device which is especially designed for use as a compressor for air and other gases, but which may also be employed as a fluid 5 pump.

There is a demand for a low pressure compressor which is efficient in operation, low in first cost and which will not become out of order. To meet these demands, the compressor must be simple and sturdy in construction and must be of proper design. One example of the use of a compressor of this requirement is in small refrigerating systems such as are used in homes and small 10 butcher shops and stores. Such small refrigerating systems employ ethyl chloride or sulphur dioxide as a refrigerant. These gases do not require high compression to function.

20 An object of my invention is to provide a compressor which is adapted for compressing low pressures but may be constructed for high pressure use.

It is a further object of my invention to 25 provide a compressor of this character which is low in first cost and upkeep by virtue of its peculiar and novel design. In my invention I provide a housing having a chamber which is of semi-cylindrical cross section. 30 In this chamber is placed a piston which is sector shape and which is of a cross section which is of less cylindrical extension than the chamber. The piston and the housing are so connected that the piston swings in 35 the chamber of the housing. Suitable valves are provided in the housing and in the piston and the operation is such that the device compresses gas.

It is a further object of my invention to 40 provide a compressor of the character mentioned which is very simple and quite rugged in construction.

It is another object of my invention to 45 provide a compressor of this character having a novel form of intake valve.

It is also an object of my invention to 50 provide a compressor of this character having a novel form of exhaust valve. The exhaust valve of my invention is very important to 55 the operation of the compressor. A cylindrical exhaust valve chamber is formed in the piston in which exhaust valve chamber is placed a valve of my invention. This valve is made from a sheet which is rolled 60 into cylindrical form. It is secured in the

chamber in such a manner that the valve portion thereof closing ports in the piston is resiliently retained in close contact with the cylindrical wall of the chamber.

It is a still further object of my invention 60 to provide a compressor having replaceable liners. These liners, when worn, may be replaced by new liners and any play of the working parts of the compressor may be cheaply and readily removed. 65

It is also an object of my invention to provide a double acting compressor of the general type set forth heretofore.

A further object of my invention is to provide a compressor which may be directly 70 connected with a motor.

Other objects and the particular advantages of my invention will be set forth in the following description.

Referring to the two sheets of drawings 75 which are for illustrative purposes only and in which I illustrate a preferred form of my invention,

Fig. 1 is a plan view of a device employing a compressor with the features of my 80 invention.

Fig. 2 is an elevational view of Fig. 1.

Fig. 3 is an enlarged sectional view taken through a compressor embodying the features of my invention. 85

Fig. 4 is a section taken on the line 4-4 of Fig. 3, and showing clearly in detail the exhaust valve construction of my invention.

Fig. 5 is a perspective view of the exhaust valve of my invention. 90

Fig. 6 is a face view showing in detail a diametral plate, an intake valve and a pivot bar of my invention.

With particular reference to Figs. 3 to 6, 95 inclusive, of the drawings, the form of my invention shown comprises a housing 11 forming a piston chamber 12. The housing 11 consists of a semi-cylindrical member 13, plates 14, and a diametral plate 15. As clearly shown in Fig. 3, the semi-cylindrical member 13 has a semi-cylindrical face 17 which is generated on an axis indicated at 18 in Fig. 3. Placed in the chamber 12 and in engagement with the semi-cylindrical face 17 of the member 13 is a bushing plate 19 which has an inner face which is concentric with the axis 18. This bushing plate 19 is made from suitable bearing metal such as phosphor-bronze. The end plates 14 are secured to faces 20 of the semi-cylindrical 100

105

110

member 13 by screws 21 which extend into flanges 22 of the member 13. Gasket plates 23 are secured between the faces 20 of the member 13 and the end plates 14. These gaskets 23 are made from a metal having high bearing qualities, such as phosphor-bronze. The diametral plate 15 is secured to faces 25 and 26 of the member 13 and the end plates 14 by screws 27 which extend into flanges 28 of the end plates 14 and into the ends of the wall of the member 13. A gasket plate 29 is secured between the member 13 and the diametral plate 15.

The gasket plate 29 has slots 30, as clearly shown in Fig. 6, forming an intake valve 31 which is adapted to close intake ports 32 formed in the diametral plate 15.

A pivot bar 35 is secured inside the chamber 12 to the diametral plate 15 by screws 36. As clearly shown in Figs. 3 and 6, the pivot bar 35 extends concentrically along the axis 18 of the chamber 12 and has a semi-cylindrical face 37 which is generated around the axis 18.

A bearing member 39 having cylindrical bearings 40 formed on the ends thereof is secured to the exterior of the diametral plate 15 by screws 41. The bearing member 39 consists of a bar portion 44 having a cylindrical face, as shown, with which bar portion 44 the bearings 40 are integrally formed. The bearing member 39 is so situated that an axis extending through the cylindrical bearings 40 intersects the axis 18 and extends at right angles thereto. This is clearly shown in Fig. 3. The bearing member 39 is positioned so that the cylindrical bearings 40 are arranged centrally of the length of the chamber 12.

Journals 46 formed at the ends of arms 47 of a yoke 48 are carried on the cylindrical bearings 40. The arms 47 have semi-cylindrical faces 49 which engage the outer portions of the bar 44. Openings 50 are formed near the ends of the arms 47 to permit an installing and removal of the screws 41. The bearing member 39 and the yoke 48 must be assembled before the bearing member 39 is secured to the housing 11. A motor shaft 53 is secured in a suitable manner in an opening 54 of a hub 55 of the yoke 48.

In the chamber 12 is a piston 60 from which there extends a piston shaft 61, this piston shaft 61 extending from the piston 60 through openings 64 and 65 in the bushing 19 and the member 13. The piston 60 is sector shape in cross section having a semi-cylindrical face 68 which contacts the inner face of the bushing 19. End faces 69 of the piston 60 contact the inner faces of the bearing gaskets 23. The piston 60 has radial faces 71, as clearly shown in Fig. 3, which are arranged to swing very close to the inner face of the gasket 29 as will be described later. At the apex of the faces 71

is formed a semi-cylindrical bearing channel 72 which engages the semi-cylindrical face 37 of the pivot bar 35. As clearly obvious from Fig. 3, the cross section of the piston 60 is of less cylindrical extension than the chamber 12. There is, therefore, a segment-shaped cavity 73 left in the chamber 12 when the piston is in the position shown in Fig. 3.

Cylindrical exhaust valve chambers 74 are formed in the piston 60 on an axis parallel to the axis 18 of the chamber 12. The ends of the bearing chamber 74 are closed by plugs 75 which are threadably secured in place, as shown clearly in Fig. 4. Exhaust ports 76 connect between the radial faces 71 and the valve chambers 74.

Cylindrical exhaust valves 80 are secured in the chambers 74 by dowel screws 81. The heads of these dowel screws extend through openings in the valves 80 which spring into place. These cylindrical exhaust valves 80 are formed from a flat sheet 82 which is bent into cylindrical contour as clearly shown in Fig. 5. The exhaust valves 80, as clearly shown in Figs. 3 and 4, extend around the circumference of the chambers 74 in engagement with the cylindrical walls thereof. Valve portions 83 of the valves 80 extend so as to close the exhaust ports 76. Tail portions 84 are provided to give a leverage for resiliently, yet forcibly, retaining the valve portions 83 in closing positions. A passage 86 connects with the chambers 74 at a point between the tails 84. An exhaust passage 87 connects with the passage 86 and extends from the piston 60 through the piston shaft 61.

As clearly shown in Figs. 1 and 2, the shaft 53 extends through a motor 90 secured to a swingable base 91 which is pivotally mounted on a sub-base 92 by a pivot bolt 93. Teeth 94 are formed at the right hand end of the base 91 which are engaged by a worm 95 supported by a shaft 96 which extends through bearings 97. A hand wheel 98 is secured to the end of the shaft 96 whereby this shaft is rotated in a manner to rotate the worm 95. A rotation of the worm by virtue of its engagement with the teeth 94 swings the base 91. This will be described shortly.

The piston shaft 61 extends through a journal 99 secured to the base 92 by bolts 100. A stuffing box 102 is placed on the extending end 103 of the piston shaft 61, there being a pipe 105 extending from the stuffing box 102 through which compressed gases pass. The piston shaft 61 has an annular channel 106 into which a tongue 107 of a member 108 carried by the journal 99 extends. This member 108 is provided for positioning the compressor.

The operation of my compressor may be clearly understood by considering the action

of the parts of a universal joint. The housing 11, the yoke 48 and the piston 60 move in substantially the same manner as the main parts of a universal joint. It is necessary for the operation of the pump to have the shafts 53 and 61 out of alignment so that there will be a relative movement between the housing 11 and the piston 60. The greater the disalignment of the shafts 53 and 61, the greater the movement between the housing 11 and the piston 60, and consequently a larger volume of gas may be pumped. The swingable base 91 may be swung by the worm 95 so that any desired position of the shaft 53 may be obtained according to the volume of gas required.

During a rotation of the compressor, the upper radial face 71 in Fig. 3 moves from the position shown into adjacency with the member 29 similar to the position of the lower radial face 71 and returns to the position shown in this figure. During this movement, the cavity 73 decreases to a minute size and then increases to the size shown. During this movement, a cavity of similar shape is formed between the lower radial face 71 and the gasket plate 29, and when the cavity 73 is minute in size, a lower cavity will be formed which is of the size of the cavity 73 shown in the drawings. When the cavity 73 is decreasing in size, gas trapped therein is forced through the exhaust ports 76, this gas forcing the valve portion 83 away from the cylindrical wall of this chamber 74, thus allowing it to be forced into this cylindrical exhaust valve chamber 74. As the cavity 73 increases in size, the valve portion 83 returns into contact with the wall of this upper exhaust valve chamber 74, closing the upper exhaust port 76. A suction at this time is created in the cavity 73 which removes the upper intake valve 31 from closing position, permitting gas to pass through the upper intakes 32 and into the cavity 73. As the cavity 73 is again decreased in size, the operation just described is repeated. Likewise, the operation with the lower part of the compressor is exactly the same as that just described with regard to the upper part. However, the operation is out of phase and while the cavity 73 is decreasing in size, a lower cavity is increasing in size and vice versa. From this description of the operation of the pump, it will be seen that my invention provides a double acting compressor.

The gas passes from the exhaust valve chamber 74 through the passage 86, through the passage 87 and is conducted from the shaft 61 by the pipe 105 of the stuffing box 102. By swinging the base 91, the shaft 53 may be moved so that the axis thereof extends at a smaller angle to the axis of the shaft 61, thus decreasing the relative swinging movement of the housing 11 and the

piston 60. When the shafts 53 and 61 are in alignment, there will be no relative movement between the housing and piston 11 and 60, respectively, and consequently there will be no relative movement between the housing and the pistons 11 and 60, respectively, and there will be no pumping action.

My invention also provides a novel means for lubricating the piston 60. With reference to Fig. 3, the end of the hub 55 is provided with an annular oil recess 110 having a lip formation 111. Oil is introduced into this recess 110 by any suitable means. The oil, by centrifugal force, is thrown to the outer parts of the recess 110. The oil passes into oil ducts 112 which diverge slightly, as shown in Fig. 3. The ducts extend radially outwardly at 113 through the arms 47 of the yoke 48. Semi-cylindrical channels 114 are formed in the portions 49 which are connected to the portions 113 of the ducts 112 by portions 115 which extend substantially parallel to the axis of rotation of the shaft 53. Holes 116 are drilled through the bar member 44, these holes connecting with the semi-cylindrical channels 114 and with openings 117 formed in the diametral plate 15. It will be noted in Fig. 3 that the ends of the intake valves 31 cover these openings 117. The oil passes through the ducts 112 by reason of centrifugal force and passes into the openings 116 and 117. When the valves 31 are unseated, oil is drawn into a cavity by suction and provides lubrication between the walls of the piston 60 and the walls of the chamber 12. This system of lubrication is very efficient and is entirely automatic in operation.

From the foregoing description it is obvious that my compressor differentiates from the usual compressor construction. This novel construction makes it possible to provide a pump which is efficient in operation and which is very sturdy and simple in construction. The compressor, as shown, is designed to be directly connected to a motor. This is an appreciable saving as it eliminates interconnecting mechanism. The parts are few and are readily assembled together. The bushing 19 and the gasket plates 23 and 29 may be replaced when they become worn, thus cheaply removing any play from the compressor. The cylindrical exhaust valves 80 of my invention are so designed that they operate effectively and efficiently. They may be readily removed by removing one end plate 14 and a plug 75, which gives access to a chamber 74.

I claim as my invention:

1. In a device of the class described, the combination of: a housing forming a cavity of semi-cylindrical cross section; a piston swingably arranged in said cavity, said piston having a cylindrical exhaust valve chamber, an exhaust port connecting between

said valve chamber and a radial face of said piston, and an exhaust passage connected to said valve chamber, there being a sector-shaped space between said radial face and a 5 plane face of said housing, said sector-shaped space changing in size as said piston is swung; an intake valve through which fluid enters said space when same is enlarging; and a cylindrical exhaust valve engaging the 10 cylindrical wall of said exhaust valve chamber and closing said exhaust port, said exhaust valve allowing fluid to pass through said exhaust port when said space is decreasing in size.

15 2. In a device of the class described, the combination of: a housing forming a cavity of semi-cylindrical cross section; a piston swingably arranged in said cavity, said piston having a cylindrical exhaust valve 20 chamber extending parallel to the axis of said cavity, an exhaust port connecting between said valve chamber and a radial face of said piston, and an exhaust passage connected to said valve chamber, there being a 25 sector-shaped space between said radial face and a plane face of said housing, said sector-shaped space changing in size as said piston is swung; an intake valve through which fluid enters said space when same is 30 enlarging; and a cylindrical exhaust valve engaging the cylindrical wall of said exhaust valve chamber and closing said exhaust port, said exhaust valve allowing fluid to 35 pass through said exhaust port when said space is decreasing in size.

3. In a device of the class described, the combination of: a housing forming a cavity of semi-cylindrical cross section; a piston swingably arranged in said cavity, said piston 40 having a cylindrical exhaust valve chamber, an exhaust port connecting between said valve chamber and a radial face of said piston, and an exhaust passage connected to said valve chamber, there being a 45 sector-shaped space between said radial face and a plane face of said housing, said sector-shaped space changing in size as said piston is swung; an intake valve through which fluid enters said space when same is 50 enlarging; and an arcuate exhaust valve engaging the cylindrical wall of said exhaust valve chamber and closing said exhaust port, said exhaust valve allowing fluid to 55 pass through said exhaust port when said space is decreasing in size.

4. In a device of the class described, the combination of: a housing forming a cavity of semi-cylindrical cross section; a piston swingably arranged in said cavity, said piston 60 having a cylindrical exhaust valve chamber, an exhaust port connecting between said valve chamber and a radial face of said piston, and an exhaust passage connected to said valve chamber, there being a 65 sector-shaped space between said radial face

and a plane face of said housing, said sector-shaped space changing in size as said piston is swung; an intake valve through which fluid enters said space when same is enlarging; and an exhaust valve for closing said exhaust port, said exhaust valve allowing fluid to pass through said exhaust port when said space is decreasing in size, said valve operating in a radial direction 70 relatively to the axis of said exhaust valve 75 chamber.

5. In a device of the class described, the combination of: a housing forming a cavity of semi-cylindrical cross section; a piston swingably arranged in said cavity, said piston having a cylindrical exhaust valve chamber, an exhaust port connecting between said valve chamber and a radial face of said piston, and an exhaust passage connected to said valve chamber, there being a sector-shaped space between said radial face and a plane face of said housing, said sector-shaped space changing in size as said piston is swung; an intake valve through which fluid enters said space when same is enlarging; and a cylindrical exhaust valve engaging the cylindrical wall of said exhaust valve chamber and closing said exhaust port, said exhaust valve allowing fluid to 80 pass through said exhaust port when said space is decreasing in size, said valve operating in a radial direction relatively to 85 said exhaust valve chamber.

6. In a device of the class described, the combination of: a housing forming a cavity of semi-cylindrical cross section; a piston swingably arranged in said cavity, said piston having a cylindrical exhaust valve chamber, an exhaust port connecting between said valve chamber and a radial face of said piston, and an exhaust passage connected to said valve chamber, there being a sector-shaped space between said radial face and a plane face of said housing, said sector-shaped space changing in size as said piston is swung; an intake valve through which fluid enters said space when same is enlarging; and an arcuate exhaust valve engaging the cylindrical wall of said exhaust valve chamber and closing said exhaust port, said exhaust valve allowing fluid to 90 pass through said exhaust port when said space is decreasing in size, said valve operating in a radial direction relatively to 95 said exhaust valve chamber.

7. In a device of the class described, the combination of: a housing forming a cavity of semi-cylindrical cross section; a piston swingably arranged in said cavity, said piston having an exhaust valve chamber, an exhaust port connecting between said valve chamber and a radial face of said piston, and an exhaust passage connected to said valve chamber, there being a sector-shaped 100 space between said radial face and a plane 105 face of said housing, said sector-shaped space changing in size as said piston is swung; an intake valve through which fluid enters said space when same is enlarging; and an arcuate exhaust valve engaging the cylindrical wall of said exhaust valve chamber and closing said exhaust port, said exhaust valve allowing fluid to 110 pass through said exhaust port when said space is decreasing in size, said valve operating in a radial direction relatively to 115 said axis of said exhaust valve chamber.

8. In a device of the class described, the combination of: a housing forming a cavity of semi-cylindrical cross section; a piston swingably arranged in said cavity, said piston having an exhaust valve chamber, an exhaust port connecting between said valve chamber and a radial face of said piston, and an exhaust passage connected to said valve chamber, there being a sector-shaped 120 space between said radial face and a plane 125 face of said housing, said sector-shaped space changing in size as said piston is swung; an intake valve through which fluid enters said space when same is enlarging; and an arcuate exhaust valve engaging the cylindrical wall of said exhaust valve chamber and closing said exhaust port, said exhaust valve allowing fluid to 130 pass through said exhaust port when said space is decreasing in size, said valve operating in a radial direction relatively to said axis of said exhaust valve chamber.

- face of said housing, said sector-shaped space changing in size as said piston is swung; an intake valve through which fluid enters said space when same is enlarging; 5 an exhaust valve for closing said exhaust port, said exhaust valve allowing fluid to pass through said exhaust port when said space is decreasing in size; and a yoke pivoted to said housing.
- 10 8. In a device of the class described, the combination of: a housing forming a cavity of semi-cylindrical cross section; a piston swingably arranged in said cavity, said piston having an exhaust valve chamber, an 15 exhaust port connecting between said valve chamber and a radial face of said piston, and an exhaust passage connected to said valve chamber, there being a sector-shaped space between said radial face and a plane face 20 of said housing, said sector-shaped space changing in size as said piston is swung; an intake valve through which fluid enters said space when same is enlarging; an exhaust valve for closing said exhaust port, 25 said exhaust valve allowing fluid to pass through said exhaust port when said space is decreasing in size; and a yoke pivoted to said housing on an axis at right angles to the axis on which said piston swings.
- 30 9. In a device of the class described, the combination of: a housing forming a cavity of semi-cylindrical cross section; a piston swingably arranged in said cavity, said piston having an exhaust valve chamber, an 35 exhaust port connecting between said valve chamber and a radial face of said piston, and an exhaust passage connected to said valve chamber, there being a sector-shaped space between said radial face and a plane 40 face of said housing, said sector-shaped space changing in size as said piston is swung; an intake valve through which fluid enters said space when same is enlarging; an exhaust valve for closing said exhaust port, 45 said exhaust valve allowing fluid to pass through said exhaust port when said space is decreasing in size; and a yoke pivoted to said housing on an axis at right angles to and intersecting the axis on which 50 said piston swings.
10. In a device of the class described, the combination of: a housing forming a cavity of semi-cylindrical cross section; a piston swingably arranged in said cavity, said piston having an exhaust valve chamber, an 55 exhaust port connecting between said valve chamber and a radial face of said piston, and an exhaust passage connected to said valve chamber, there being a sector-shaped space 60 between said radial face and a plane face of said housing, said sector-shaped space changing in size as said piston is swung; an intake valve through which fluid enters said space when same is enlarging; an exhaust valve for closing said exhaust port, 65 said exhaust valve allowing fluid to pass through said exhaust port when said space is decreasing in size; a yoke pivoted to said housing on an axis at right angles to the axis 70 on which said piston swings; a yoke shaft extending from said yoke; and a piston shaft 75
- enlarging; and an exhaust valve for closing said exhaust port, said exhaust valve allowing fluid to pass through said exhaust port when said space is decreasing in size.
11. In a device of the class described, the 80 combination of: a housing forming a cavity of semi-cylindrical cross section; a piston swingably arranged in said cavity, said piston having a cylindrical exhaust valve chamber, an exhaust port connecting between 85 said valve chamber and a radial face of said piston, and an exhaust passage connected to said valve chamber, there being a sector-shaped space between said radial face and a plane face of said housing, said sector-shaped space changing in size as said piston is swung; plugs for closing the ends of said exhaust valve chamber; an intake valve through which fluid enters said space when same is enlarging; and an exhaust valve for closing said exhaust port, said exhaust valve allowing fluid to pass through said exhaust port when said space is decreasing in size.
12. In a device of the class described, the 90 combination of: a housing forming a cavity of semi-cylindrical cross section; a piston swingably arranged in said cavity, said piston having a cylindrical exhaust valve chamber, an exhaust port connecting between 95 said valve chamber and a radial face of said piston, and an exhaust passage connected to said valve chamber, there being a sector-shaped space between said radial face and a plane face of said housing, said sector-shaped space changing in size as said piston is swung; plugs for closing the ends of said exhaust valve chamber; an intake valve through which fluid enters said space when same is enlarging; and a cylindrical exhaust 100 valve engaging the cylindrical wall of said exhaust valve chamber and closing said exhaust port, said exhaust valve allowing fluid to pass through said exhaust port when said space is decreasing in size.
13. In a device of the class described, the 105 combination of: a housing forming a cavity of semi-cylindrical cross section; a piston swingably arranged in said cavity, said piston having an exhaust valve chamber, an exhaust port connecting between said valve 110 chamber and a radial face of said piston, and an exhaust passage connected to said valve chamber, there being a sector-shaped space between said radial face and a plane face of said housing, said sector-shaped space changing in size as said piston is swung; an intake valve through which fluid enters said space when same is enlarging; an exhaust valve for closing said exhaust port, 115 said exhaust valve allowing fluid to pass through said exhaust port when said space is decreasing in size; a yoke pivoted to said housing on an axis at right angles to the axis on which said piston swings; a yoke shaft 120 extending from said yoke; and a piston shaft 125
- 120
- 125
- 130

extending from said piston to the exterior of said housing.

14. In a device of the class described, the combination of: a housing forming a cavity of semi-cylindrical cross section, said housing including a diametral plate having intake ports therein; a piston swingably arranged in said cavity, there being a sector-shaped space between a face of said piston and said diametral plate, said sector-shaped space changing in size as said piston is swung; an exhaust valve carried by said piston; and an intake valve adapted to open and close said intake ports.

15. In a device of the class described, the combination of: a housing forming a cavity of semi-cylindrical cross section, said housing including a diametral plate having intake ports therein; a piston swingably arranged in said cavity, there being a sector-shaped space between a face of said piston and said diametral plate, said sector-shaped space changing in size as said piston is swung; an exhaust valve carried by said piston; and an intake valve adapted to open and close said intake ports, said intake valve comprising a gasket plate adapted to close said intake ports when said space is decreasing in size and to open said ports when said space is increasing in size.

16. In a device of the class described, the combination of: a housing forming a cavity of semi-cylindrical cross section, said housing including a diametral plate having intake ports therein; a piston swingably arranged in said cavity, there being a sector-shaped space between a face of said piston and said diametral plate, said sector-shaped space changing in size as said piston is swung; an exhaust valve carried by said piston; and an intake valve adapted to open and close said intake ports, said intake valve comprising a gasket plate adapted to close said intake ports when said space is decreasing in size and to open said ports when said space is increasing in size, there being slots in said gasket plate allowing passage of fluid to the said space when said intake ports are open.

17. In a device of the class described, the combination of: a housing forming a cavity of semi-cylindrical cross section, said housing including a diametral plate having intake ports therein; a piston swingably arranged in said cavity, said piston having an exhaust valve chamber, an exhaust port connecting between said valve chamber and a

radial face of said piston, and an exhaust passage connected to said valve chamber, there being a sector-shaped space between 60 said radial face and the diametral plate, said space changing in size as said piston is swung; an intake valve adapted to open and close said intake ports by which fluid enters said space when same is enlarging; and an 65 exhaust valve for closing said exhaust port, said exhaust valve allowing fluid to pass through said exhaust port when said space is decreasing in size.

18. In a device of the class described, the combination of: a housing forming a cavity of semi-cylindrical cross section; a bushing plate lining the semi-cylindrical portion of said housing, thereby partly defining said 75 cavity; a piston swingably arranged in said cavity, said piston having an exhaust valve chamber, an exhaust port connecting between said valve chamber and a radial face of said piston, and an exhaust passage connected to said valve chamber, there being 80 a sector-shaped space between said radial face and a plane face of said housing, said sector-shaped space changing in size as said piston is swung; an intake valve through 85 which fluid enters said space when same is enlarging; and an exhaust valve for closing said exhaust port, said exhaust valve allowing fluid to pass through said exhaust port when said space is decreasing in size.

19. In a device of the class described, the combination of: a housing forming a cavity of semi-cylindrical cross section; a bushing plate lining the semi-cylindrical portion of said housing thereby partly defining said 95 cavity; a piston swingably arranged in said cavity, the sides of said piston engaging the said bushing plate lining; intake valves communicating with said cavity; and exhaust valves communicating with said cavity.

20. In a device of the class described, the combination of: a housing forming a cavity of semi-cylindrical cross section, said housing including a flat diametral plate having inlet ports therein; a piston swingably arranged in said cavity; an intake valve communicating with said cavity, said valve comprising a gasket plate adapted to open and close said inlet ports; and an exhaust valve communicating with said cavity.

In testimony whereof, I have hereunto set 110 my hand at Los Angeles, California, this 12th day of Sept., 1925.

FRANK E. HOLMES.
